[57] CLAIM

The ornamental design for a snow sail sled, as shown
and described.

DESCRIPTION

FIG. 1 is a perspective view of a snow sail sled showing
my new design, it being understood that the broken
lines are for illustrative purposes only;
FIG. 2 is a front elevation view thereof;
FIG. 3 is an enlarged side elevation view thereof; and
FIG. 4 is an enlarged top plan view thereof.

FIG.1.

FIG.2.

FIG. 4.
